GOLD MINING MACHINERY

Robert G. Neider, Boise, Idaho, assignor to The
Submarine Gold Mining Company, Boise,
Idaho, a corporation of Idaho

Application May 15, 1937, Serial No. 142,892

11 Claims. (Cl. 262—2)

This invention relates to gold mining machinery and particularly to means for recovering gold from the sands of river bottoms or other places under water.

One object of this invention is to provide means for this purpose, including a barge, a diving bell movable through the barge, the barge having means whereby the diving bell may be raised or lowered, and means being provided in the form of spuds for guiding the bell downward in place on the river bottom to prevent the bell from being shifted out of its designed place by strong currents.

Another object is to provide a diving bell having a man-way leading downward into the bell and having a length greater than the depth to which the bell is to be sunk whereby access may be had at all times to the interior of the bell, this man-way being provided with air locks.

A further object is to provide the diving bell with a sluice box and a receptacle or compartment for the tailings discharged from the sluice box and provide means whereby water may be caused to flow down over the sluice box to separate the gold from the sand and lighter materials and whereby the tailings may be sucked up by a sand pump and then, if necessary, reconcentrated.

A further object is to provide the barge with means whereby the diving bell may be raised or lowered and means for supporting the spuds in a raised position and then allowing the spuds to drop of their own weight into the river bed to act as guides for the diving bell, and provide means whereby the spuds may be raised when any particular diving operation is finished and it is desired to move the barge to a new position.

Other objects will appear in the course of the following description.

My invention is illustrated in the accompanying drawings wherein:

Fig. 1 is a side elevation of a barge and diving bell constructed in accordance with my invention, the hull being broken away to show the diving bell.

Fig. 2 is a top plan view of the structure shown in Fig. 1, the upper works being omitted.

Fig. 3 is a vertical section of the tower whereby access is had to the interior of the diving bell.

Fig. 4 is a section on the line 4—4 of Fig. 3.

Fig. 5 is a detailed fragmentary elevation of one of the spuds and its guide and showing a pawl whereby the spud is held raised.

Fig. 6 is a section on the line 6—6 of Fig. 5.

Fig. 7 is an enlarged vertical sectional view

through the diving bell and showing the packing apron in place against the bottom of the river.

Fig. 8 is a fragmentary sectional view on the line 8—8 of Fig. 1, the section being on an enlarged scale.

Fig. 9 is a fragmentary vertical sectional view through the apron and showing the pockets therein.

Referring to Fig. 1, 10 designates a barge which may be of any suitable construction and only a portion of which is illustrated in the figures. The central portion of the barge is formed to provide an opening 11. Supported above this opening by suitable vertical members 12 are the two cross-beams 13 which support the pulley block 14 over the center of the opening 11. These beams 13 also support the pulleys 15 and 16 over which are trained the cables which operate the spuds, as will be later described.

Adapted to be lowered or raised through the opening 11 is a diving bell 17 which, as illustrated, has a pointed or bow end 18. This diving bell may be constructed of heavy sheet metal and is sunk to the required depth by cast iron weights. This bell is raised by means of a power hoist on the deck of the barge. The provision of a pointed bow 18 on the diving bell provides less resistance to the water if the barge and bell be turned so that the pointed or bow end of the bell is directed toward the oncoming stream or current. The bell is illustrated as supported by means of a pulley block 19 engaged by a cable 20 with the pulley block 14 in an obvious and well known manner. This cable 20 passes from the pulley block 14 over a sheave 21 supported on the beams 13 and from thence passes down to any suitable power hoist.

The interior of the bell is provided with a longitudinally extending sluice box 22 preferably having riffles on its upper face and preferably being inclined downward from one end of the bell toward the other end thereof. This sluice box discharges its tailings into a compartment 23. The operators within the bell dig out the sand upon which the bell rests and throw the sand or gravel into the sluice box. A water pipe 24 discharges into this sluice box. A suction hose 25 is disposed within the bell and has its lower end provided with a cage 26 and draws the fine tailings from the tailings compartment 23, as will be later stated.

For the purpose of permitting entrance and exit to the diving bell at all times, one end of the bell is provided with a vertically extending tubular man-way tower 27. This extends upward

above the bell a distance equal to the greatest depth to which the bell is likely to be lowered and is formed to provide an entrance opening at its upper end closed by a door 28. Intermediate the length of the tower 27 there is a second door 29, these doors 28 and 29 constituting air locks. A ladder 30 extends downward from the top of the tower 27 to the bottom of the bell. Air under compression is discharged into the interior of the bell by means of the air pipe 31. The pipes 24, 25, and 31 are extended upward exteriorly of the tower 27 and are supported for movement with this tower and with the bell by means of the brackets 32. At their upper ends, 15 these three pipes are connected to flexible pipes 33, 34, and 35, whereby these pipes may be respectively connected to a water pump, to a sand pump and to an air pump all mounted upon the deck of the barge.

20 For the purpose of guiding the bell in its downward movement so as to sink the bell with certainty at a particular spot in the bed of the stream or river, I provide the spuds 36 disposed one at each end of the opening 11. These 25 spuds are pointed at their lower ends, of course, and they are intended to be allowed to drop from the barge straight downward and to enter the bed of the river. The spuds are relatively heavy, of course, and are guided in their vertical 30 movements by eyes 37. There are any desired number of these guides 37 attached to the vertical members 12 and through which the spuds loosely pass. The bell 17 is also provided at each end with a plurality of guides 38 having 35 eyes through which the spud loosely passes. The spuds are raised or held in a raised position by means of collars 39 each provided with a pawl 40. The other end of each pawl is connected to a cable 41 which passes over the respective 40 sheaves 45 and 46 and down to spud winches 42 and 43. As long as these cables are taut, the pawls 40 will engage with the spuds and hold them raised. When the cables are slackened, the pawls will trip and permit the descent under 45 their own weight of the spuds 36 which will thus be driven into the bed of the river, the spuds sliding through the collars 39, the guides 37 and the guides 38. After the spuds have dropped and embedded their lower ends in the bed of the 50 river, the diving bell is then lowered onto the river bed and is guided in its descent by these previously embedded spuds. Provision must be made, of course, for preventing the inlet of water around the lower edge of the bell and for 55 packing the point of contact between the lower edge of the bell and the river bottom.

To this end, I have provided a canvas apron or annular bag designated generally 44, the upper edge of which annular bag is attached to the 60 lower margin of the bell. This annular canvas bag is partially filled with sand designated 45 in Fig. 7. Preferably, the interior of the annular canvas bag is separated by canvas partitions 46 so as to form a series of sand containing compartments within the annular bag. The upper margin of the annular bag or apron extends upward, then inward and downward and is wrapped around an annular iron band 47. Attached to the lower edge of the bell at intervals are upwardly and outwardly extending arms 48 whose upper ends are spaced from the outer face of the bell and the iron 47 is disposed in this space. A set screw 49 extends through the upper end of each of the arms 48 and bears against the 70 outer surface of that portion of the canvas which

is wrapped around the annular iron 47 or band and this set screw forces the canvas and the two folds of canvas and the band 47 tightly against the face of the bell sufficiently so as to prevent any entrance of water at this point. 5 With this construction, it is obvious that the canvas apron or annular bag 44 will normally, and when the bell is raised, depend to its full extent from the bottom of the bell and then as the bell is lowered onto the bed of the stream, 10 this apron or annular bag-like packing will spread laterally and the sand with which it is weighted will cause the undersurface of this bag-like element to conform to the surface of the stream. This action is illustrated in Fig. 7. 15

The barge, as before stated, may be of any suitable construction and it is designed that the barge shall support a tool house having suitable tools, forges, etc., whereby repairs may be made to the mechanism carried by the barge or 20 the mechanism within the diving bell. The barge will also preferably be provided with a second building or house having therein room for offices, a dining hall, kitchen etc., and sleeping quarters for the men. I have not illustrated 25 these particular details in the drawings as it is obvious that these details will form no part of my invention and might be varied in many ways. It is necessary, however, that the barge shall have means whereby it may be maneuvered into 30 any particular position on the river or stream and to this end the forward corners of the barge are provided with hand winches 50 having lines running to the shore, so that by winding up or paying out these lines, the barge may be maneuvered into the proper position and then held in this position. Of course, it is obvious that the barge might have engine-operated means whereby it could be shifted and then the shore lines 35 coming from the winches 50 would hold the barge 40 in the position desired. To a certain extent also, the spuds 36 will hold the barge in a set position as well as act as guides for the bell.

While I, of course, do not wish to be limited to any particular means for forcing water 45 through the water pipe 24 to the sluice box 22 or for withdrawing the sand or tailings through the pipe 25 or discharging compressed air into the interior of the bell, I have shown for the purpose of air compressing the compressor 51 50 discharging into an air tank 52 from which the pipe 36 extends. The water pipe 24 is connected by the flexible hose 33 to the discharge pipe 53 of a water pump 54 while the sand pipe 25 is connected by the flexible pipe 34 to the sand 55 pump 55.

A winding drum 56 is provided over which the cable 20 passes, this winding drum having a gear wheel 57 driven by a gear wheel 58 on a shaft 59 which in turn is driven from a line shaft 60 in turn driven from the shaft of a motor 61, this motor preferably being in the form of a 25-horse-power Diesel engine. The sand pump is driven from this line shaft 60 and the water pump is also driven from this line shaft. Of course, suitable clutches are provided whereby any or all of these instrumentalities may be selectively operated or operatively disconnected from the line shaft 60.

The interior of the bell is illuminated by an 70 electric lamp 62 connected by wires to a generator 63 mounted on the barge. The interior of the bell is provided, of course, with a telephone whereby communication may be had with the men on the barge, and with a signal button 64. 75

The bell is also provided with an air discharge element 65 so as to maintain a circulation of air and permit the introduction of fresh air into the bell at all times. The barge preferably will be 5 made to provide six water-tight compartments, these compartments being provided with valves for flooding in case of listing due to accidents or for other reasons. The barge, of course, will be 10 of very shallow draft as it is intended that this barge will operate in water from 2 to 20 feet deep 15 though it can be used for greater depths, if necessary.

There are three particularly important features in my construction, namely, the apron 44, 15 the spuds 36 and the sluice box disposed within 20 the bell. When the bell is lowered, the apron will touch the high bed rock first, then the edge of the 25 bell will settle in the sand of the apron and on the high part of the bed rock. The apron will hang 30 straight down to the lower bed rock and conform thereto, thus enabling the operators in the bell 35 to work and clean up this irregular bed rock under compressed air and without any water interfering with their operations due to the irregularity 40 in the bed rock. The two spuds 36, when lowered, serve as guides to direct the raising and lowering of the submarine bell, the bell being provided with shoes 38 that fit around the spuds but move with facility on any upward or downward 45 action of the bell. The spuds serve the purpose of keeping the bell in place despite rapid currents and insure immovability under working conditions. The sluice box permits the sand, 50 gravel or rock which has been dug out from the bed of the river to be concentrated by the riffles 55 of the sluice box and the suction line 25 permits the fines or tailings to be lifted out of the way and reconcentrated on the deck of the barge if desirable. I have not shown any reconcentrating 60 apparatus as any suitable concentrating apparatus might be used, the sand pump 55 discharging onto this concentrating apparatus if it is desired to reconcentrate.

It will be understood that the bell is entered 45 through the man-way tower which, as illustrated, is formed in sections so that if the work is to be 50 done at considerable depth, new sections may be added to the tower, and so that the upper end of the tower is always clear above the water for 55 at least 2 or 3 feet. The doors 28 and 29 within the tower serve as air locks. A workman entering 60 the bell must first enter the upper portion of the tower and lock the steel trap door behind him. He may then open the second door to thus permit 65 the pressure within the bell and within the lower portion of the tower to equalize or an air line 66 may be provided between the interior of the bell and the lower portion of the tower to equalize the air pressure. After the air pressure is equalized, 70 he then enters the bell itself. The second door 29 is left open while he is working so that in case of an accident, the worker can climb above the water level. The flexible hose constituting the water line, the air line, the tailings, suction line 75 and the cable containing the wires for the electric lights, telephone, etc., are protected by the pointed end 18 of the bell which constitutes a shield for the tower and which also serves to break the flow of water.

In the beginning of the work with my apparatus and after the bell has been lowered into position, the workmen handle the suction hose moving the nozzle here and there, and by the means of this suction hose or the sand pump take 75 up all the loose gravel, sand and muck which is

pumped to the sluice box 67 shown in Fig. 2, this sluice box being located alongside the barge on the deck where this gravel is washed for gold. The sluice box 67 is provided with riffles in the usual manner. After all of the over-burden has 5 been pumped out and into the sluice box 67 and the bed rock is fairly clean, the sand pump 54 is shut down and the pump which forces water through the pipe 24 is started. The workmen clean the bed rock and crevices thoroughly and 10 wash the gravel so gathered in the sluice box 22. The compartment 23 acts as a container for the gravel or fines which are washed out of the end of the sluice box and this is pumped out by the sand pump 54 only in case too much material is 15 found in the crevices and has to be disposed of so as to keep the bell from becoming crowded with gravel. Pump 54 furnishes the water to the pipe line 24 to wash the gravel and other matters in the sluice box 22. The gravel is shoveled into this 20 sluice box by hand. The tower sections 27 are preferably made in 4 ft. lengths with gaskets between the bolted ends of the sections.

While I have illustrated certain details of construction and certain particular arrangement of parts, it is obvious that many changes might be made in these details without departing from the spirit of the invention as defined in the appended claims.

What is claimed is:—

1. A mining apparatus of the character described, including a barge, a diving bell, means supporting the diving bell on the barge, power operated means for raising or lowering the bell, means maintaining a predetermined air pressure 35 within the bell, a man-way tower extending upward from the bell and having locks, means whereby the pressure of air between the locks of the tower may be equalized, a sluice box disposed within the diving bell and discharging into a 40 tailings compartment, a pump on the barge, a flexible pipe extending from the pump into the bell and discharging into the sluice box, and a suction line extending from the tailings compartment to the barge and a sand pump connected to 45 the suction line.

2. An apparatus of the character described, including a barge having an opening in its center, a diving bell disposed within said opening, power operated means for raising or lowering the diving 50 bell including a cable directly supporting the bell, spuds slidably supported in said opening of the barge, guide members on the diving bell through which said spuds loosely pass, means for raising the spuds or holding them in raised position, and 55 means for releasing the raising means from the spuds to permit the spuds to drop and engage the bed of the stream, the spuds acting as guides for the diving bell.

3. An apparatus of the character described, 60 including a barge having an opening in its center, a diving bell disposed within said opening, power operated means for raising or lowering the diving bell, spuds slidably supported in said opening of the barge, guide members on the diving bell 65 through which said spuds loosely pass, means for raising the spuds or holding them in raised position, including winches, cables connected to the winches, pulleys supported upon the barge adjacent the spuds and above the deck of the barge 70 and over which the cables pass, guides mounted upon the barge through which the spuds loosely pass, a collar for each spud loosely embracing the spud, a pawl on each collar adapted to bite into the corresponding spud, the cables being attached 75

- to the outer ends of the pawls, the pawls permitting the downward movement of the spuds upon a slackening of the cables and guides on the diving bell having sliding engagement with the 5 spuds and permitting the spuds and diving bell to have relatively vertical movement.
4. An apparatus of the character described, including a barge having a central vertical opening, uprights on each side of said opening and 10 mounted on the barge, transverse beams carried by the uprights, a diving bell disposed in said opening, coacting tackle blocks mounted respectively upon the diving bell and upon the transverse beams, hoisting mechanism disposed on the barge, a cable passing over said blocks and connected to the hoisting means, a tower mounted upon the diving bell and opening into the interior 15 thereof and extending upward therefrom, the tower having a plurality of doors constituting air locks and having a ladder, means for supplying compressed air to the interior of the diving bell, means for guiding the bell in its vertical movement and anchoring the bell in predetermined position below the barge and against accidental 20 movement, a sluice box disposed within the bell, the bell having a tailings compartment into which the sluice box discharges, a pump on the barge, a water pipe extending from the pump into the bell and discharging onto the sluice box, a suction line extending from the tailings compartment out of the bell and operatively connected to a sand pump, means for forcing compressed air into the bell, and means for permitting the predetermined discharge of air from the bell.
- 35 5. An apparatus of the character described, including a barge having a central opening, a diving bell disposed within said central opening, means for raising the diving bell to a level with the barge or lowering it below the level of the 40 barge, a tubular tower carried by the bell and having an entrance opening and a ladder leading into the bell, the tower having air locks, vertically extending spuds supported upon the barge at each 45 end of the diving bell and having vertical movement independent of the diving bell, means for holding the spuds in a raised position or releasing said spuds to permit them to descend of their own weight and embed themselves in the bed of the stream, and guides mounted at opposite ends 50 of the bell and slidingly engaging said spuds.
6. An apparatus of the character described, including a barge, a diving bell associated with the barge, power operated means on the barge for raising or lowering the diving bell, a tubular 55 tower extending upward from the diving bell and having air locks and a ladder whereby access may be had to the interior of the bell, a rifled sluice box disposed within the interior of the bell and

inclined in one direction, a tailings compartment into which the sluice box discharges, a water inlet pipe discharging against the upper end of the sluice box, a pump on the barge, a flexible pipe connecting the inlet pipe of the pump, a 5 suction line extending from the tailings compartment, a sand pump on the barge, flexible hose connecting the suction line with the sand pump, and means on the barge for forcing air under pressure into the interior of the diving bell. 10

7. A diving bell having on its lower end an annular bag of flexible material and partially filled with granulated material, the bag extending entirely around the bell and at its upper end having water-tight engagement with the bell, the 15 bag normally depending below the lower edge of the bell.

8. A diving bell having on its lower end a flexible annular bag of flexible material, the bag being divided into pockets by transversely 20 extending flexible members, the interior of said pockets being partially filled with granular material, the upper end of the bag being attached to and having water-tight contact with the surface of the bell entirely around its periphery. 25

9. A diving bell having on its lower end an annular bag of flexible material and partially filled with granulated material, the bag extending entirely around the bell, an annular metallic band extending around the lower portion of the 30 diving bell and around which band the upper end of said bag is wrapped, and means for clamping the band tightly against the outer face of the bell.

10. A diving bell having on its lower end an annular bag of flexible material and partially 35 filled with granulated material, the bag extending entirely around the bell, an annular metallic band extending around the lower portion of the diving bell and around which band the upper end of said bag is wrapped, a plurality of upwardly 40 and outwardly extending irons attached to the lower end of the bell, said band being disposed in the space between the upper ends of said irons and the bell, and set screws extending through the upper ends of the irons and bearing against the 45 band to thereby force the band towards the bell and compress the folds of the bag thereagainst.

11. A diving bell having a packing member attached to the bottom of the bell entirely around the bell and hanging freely therefrom, the packing member being formed of flexible material and being in the form of a bag divided into pockets, the bag being partially filled with relatively heavy 50 granular material whereby the bag will contact with the bed of a stream and conform to the contour thereof when the diving bell is lowered. 55

ROBERT G. NEIDER.
